UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A STANDARD FOR LIGHTING FIXTURES.

61,226.

Specification for Design.

Patented July 18, 1922.

Application filed September 12, 1921. Serial No. 500,216. Term of patent 14 years.

To all whom it may concern:

Be it known that I, JOSEPH W. GOSLING, a citizen of the United States, residing at Schenectady, in the county of Schenectady and State of New York, have invented a new, original, and ornamental Design for a Standard for Lighting Fixtures, of which the following is a specification, reference being had to the accompanying drawing, forming a part thereof.

The drawing is a front elevation of an ornamental standard of my invention for street lighting fixtures.

I claim:

The ornamental design for a standard for lighting fixtures as shown.

In witness whereof, I have hereunto set my hand this 10th day of September, 1921.

JOSEPH W. GOSLING.
